UNITED STATES PATENT OFFICE.

FRED L. MANNY, OF BENTON HARBOR, MICHIGAN, ASSIGNOR TO BAKER-VAWTER COMPANY, OF BENTON HARBOR, MICHIGAN, A CORPORATION OF MICHIGAN.

BINDER.

1,346,328.

Specification of Letters Patent. Patented July 13, 1920.

Application filed October 2, 1917. Serial No. 194,349.

To all whom it may concern:

Be it known that I, FRED L. MANNY, a citizen of the United States, residing at Benton Harbor, in the county of Berrien 5 and State of Michigan, have invented certain new and useful Improvements in Binders, of which the following is a specification.

My invention relates to binders designed 10 to hold bodies of unconnected perforated sheets in the form of ledgers or account books of any sort of the loose leaf type. The object of my invention is to provide a simple and effective locking mechanism, 15 housed in a hollow binding plate member hinged to one of the covers of the binder, for attaching such binding plate and cover of the binder structure to posts carried by a coöperating plate hingedly connected 20 with the other cover. My invention consists in the combination, arrangement and organization of coöperating parts making up and associated with this locking mechanism, the essential elements of which will 25 be more particularly pointed out in the appended claims.

Of the drawing Figure 1 is an outside view of the binder cover and attached hinged binding plate member on the line 30 1-1 of Fig. 2, showing the cover plate removed to disclose the locking mechanism; Fig. 2 is a cross-section on the line 2-2 of Fig. 1; Fig. 3 is a fragmentary view of a corner of the binder looking in the opposite direction from the view point of Fig. 2; and Fig. 4 is a detail showing the cover plate of the hollow binding plate member which houses the locking mechanism partially removed.

40 The same reference characters indicate the same parts in all the figures of the drawing.

The covers 1 of the binder, formed of any suitable material, as for instance a strong compact fiber board, are flexibly connected by hinge plates 2 with the strips 3, each of which forms part of a hollow casing constituting a post plate or binding plate member, both binding plates being for symmetry of appearance and convenience of 45 construction formed alike, and one of them being arranged to house the locking mechanism hereinafter described. These casings or binding plates each comprise the strip 3, a plate 4 spot-welded thereto and 50 formed with flanges 4^a outwardly bent or

rolled at their edges, and a cover plate 5 provided with flanges 5^a recurved to slidably engage and interlock with the flanges 4^a.

Rigidly secured to the lower binding plate 60 (using the word "lower" with reference to the position of parts shown in Fig. 2) are the base portions of sectional posts 6 which are designed to engage the perforations or slots of the sheet 21 which the binder is 65 constructed to receive. The plates 3, 4 and 5 of the upper binding plate member are formed with registering orifices to receive the posts 6, the tip portions of which project above and beyond the top cover 1, as shown 70 in Fig. 2. Preferably the top binding plate is also equipped with posts 6^a (see Fig. 1), these posts, however, being made shorter than the posts 6, so that they will only extend to or near the imperforate cover plate 75 5 of the lower binding plate. In the practical use of the binder the proper length of the posts 6 and 6^a is attained by employing such number of intermediate sections between the base and tip of the different posts 80 as may be needed.

The gripping or locking mechanism housed in the space between the plate 4 and cover plate 5 of the upper binding plate member consists of a sliding block 7 formed 85 with an inclined face 7^a arranged to impinge against the post 6 adjacent one end of the back of the binder, and a second sliding block 8 formed with an inclined face 8^a arranged to impinge against the post 6 adjacent the opposite end of the back, the block 7 being secured to a rod 9 internally screw-threaded at the end opposite the block 7, and the block 8 being engaged by the shouldered outer portion 10 of a screw rod 11, which, 90 at its inner end makes threaded engagement with the threaded bore of the rod 9 and at its outer end is formed with a squared shank 12 adapted to receive a key by which it may be turned. An extension 100 13 of the block 7 is formed with lugs 14 arranged on opposite sides of a stop lug 15 secured to the plate 4, a small coiled spring 16 between the stop and one of the lugs serving to yieldingly urge the block 105 7 out of engagement with the adjacent post 6. The narrow edge of the block 8 is arranged between a pair of stop lugs 17 secured to the plate 4 and a small coiled compression spring 18 seated in a socket in 110

such block and bearing against one of said lugs yieldingly tends to urge the block away from engagement with its adjacent post 6. It can readily be seen that by turning the operating key to draw the rods 9 and 11 together the inclined faces 7^a and 8^a of the blocks 7 and 8 will impinge against the associated posts 6 and grip them with a wedging action against the sides of the orifices in the plates 3, 4 and 5, the backs of the blocks sliding on the adjacent flange 4^a of the plate 4 which sustains the thrust of the wedge faces, and the binding plate will thus be firmly locked on the posts. When the key is turned in the opposite direction the springs 15 and 18 will react against the blocks to shift them out of contact with the posts, the lugs 14 and 17 acting as stops to restrain excess movement and thus release the posts from locked engagement.

To provide a neat and sightly finish shouldered corner blocks 19 are provided, such blocks being secured in place by screws 20 passing through the plates 3 and 4 and holding the cover plates 5 in place. The particular block 19 adjacent the screw rod 11 is channeled to receive the outer end of such rod, and permit insertion of the key for turning it.

30 I claim:

1. In a binder equipped with a pair of posts, post-engaging means comprising a plate member formed with a longitudinal face adapted to receive a lateral thrust, a 35 clamping block arranged to slidingly engage said face of said plate and formed with an inclined face, said block being provided with a stem having a hollow, internally-threaded inner end, a screw rod having a threaded

inner end engaging said stem and formed 40 with a shoulder adjacent its outer end, and a second clamping block loosely engaging said screw rod and coöperating with said shoulder and also arranged to slidingly engage said face of said plate member, said screw rod being manually rotatable to draw said clamping blocks toward each other and into wedging engagement between said posts and said longitudinal faces on the plate member.

2. In a binder having a pair of covers and a post-plate equipped with posts attached to one cover, a hollow orificed casing, forming the opposite post plate and equipped with inclosed locking mechanism 45 arranged to engage said posts, said casing comprising a longitudinal flanged plate, a flanged cover plate making interlocking sliding engagement with said first-mentioned casing plate, and shouldered corner 50 blocks seated in the ends of said casing and secured to said first-mentioned casing plate to prevent displacement of the cover plate.

3. In a binder having a pair of covers and a post-plate equipped with posts attached to one cover, a hollow orificed casing forming the opposite post plate and equipped with inclosed locking mechanism arranged to engage said posts, said casing comprising a longitudinal flanged plate, a flanged cover 55 plate making interlocking sliding engagement with said first-mentioned casing plate, and shouldered corner blocks seated in the ends of said casing and both secured to one of said casing plates to prevent displacement of one plate relatively to the other 60

FRED L. MANNY.
